PURIFICATION OF NAPHTHENIC ACIDS

Wilmer E. McCorquodale, Jr., Ardentown, Del.,
assignor to Sun Oil Company, Philadelphia,
Pa., a corporation of New Jersey

Application October 14, 1942, Serial No. 462,039

7 Claims. (Cl. 260—514)

The present invention relates to a method of obtaining naphthenic or petroleum acids of any desired degree of purity from mixtures of such naphthenic acids and neutral hydrocarbon oils.

The organic acids derived from petroleum have found wide and varied uses in numerous arts. These acids will be referred to herein as naphthenic acids and it is to be understood that this term is used herein in a broad sense and includes not only the true naphthenic acids of the series of $C_nH_{2n-2}O_2$ but also acids of other series such as $C_nH_{2n-x}O_2$ in which x may vary from 2 to 8 or higher, and which are derived from petroleum, all of which are commonly referred to as petroleum naphthenic acids. However, such naphthenic acids are generally present in relatively small amounts in any given crude petroleum and it is difficult to obtain them in any relatively pure form. While for many uses, for instance in the manufacture of emulsifiable oils, the acids or more particularly their soaps are used in admixture with neutral hydrocarbon oils and it is therefore not necessary to purify the acids extensively, for many of the more recently developed uses, for instance as plasticizers in rubber manufacture, naphthenic acids which are substantially free of neutral oils must be obtained and there is at present a considerable market for pure naphthenic acids; and for many of the uses to which these acids are now put naphthenic acids containing two per cent or less of neutral oils are specified.

In order to produce acids of this degree of purity by known processes, the acids are generally converted into their corresponding soaps and the soaps are then separated from the oil by solvent extraction or distillation or some combination of distillation and solvent extraction. The soaps must then be acidified to convert them back into their corresponding naphthenic acids and the naphthenic acids thus obtained then desalts. Such purification methods require relatively large amounts of chemicals (alkali and mineral acid) which are generally lost as salt, so that the chemical costs of such processes are quite substantial.

Efforts have been made to separate the naphthenic acids from neutral hydrocarbon oils by straight solvent extraction without saponification of the acids. However, such straight solvent extraction processes as have been suggested involve the use of solvents with which mixtures of naphthenic acids and oil containing less than a certain amount of oil are miscible in all proportions and therefore by known solvent extrac-

tion methods it is impossible to obtain naphthenic acids of a relatively high degree of purity.

The present invention is therefore directed to a method of straight solvent extraction of naphthenic acids, without saponification of the acids, in which the solvent employed is one which while it has preferential solvency for naphthenic acids is not completely miscible with naphthenic acids, and in which the extraction conditions employed are such that naphthenic acids of any desired degree of purity may be obtained.

In order to more readily describe the present invention there is attached hereto drawings in which:

Fig. 1 is a diagrammatic flow chart of apparatus suitable for practicing the present invention.

Fig. 2 is a phase diagram of the system, naphthenic acids—oil and solvent in which the solvent employed is miscible with the naphthenic acids in all proportions, while

Fig. 3 is a phase diagram of the system, naphthenic acids—oil and solvent in which the solvent employed is not completely miscible with naphthenic acids.

Among the solvents which have been suggested for purification of naphthenic acids are methanol and glacial acetic acid. However, when these solvents are employed a phase diagram of the type illustrated in Fig. 2 is obtained and naphthenic acids of a greater purity than M cannot be obtained, no matter what extraction conditions are employed. I have discovered that if any polar organic liquid having preferential solvency for naphthenic acids but which is not completely miscible therewith is employed, rather than a completely miscible solvent such as those heretofore suggested, a system of the type illustrated in Fig. 3 may be obtained and, by the use of proper extraction conditions; i. e. by using sufficient reflux and the proper number of extraction stages, naphthenic acids of any desired degree of purity may be obtained. In practicing the present invention I may employ either a single solvent which has selective preferential solvency for naphthenic acids and which is not completely miscible with naphthenic acids; or I may employ one of the solvents already known to have preferential solvency for naphthenic acids but which is completely miscible, and add to such solvent a second liquid which causes its miscibility with naphthenic acids to decrease. Among the solvents which I have found to be suitable are: methanol containing no less than 12 vol. per cent water; 55 methanol containing no less than 26.5 vol. per

cent of commercial formic acid (or including the water, the actual composition of this solvent is 73.5 per cent methanol, 22.7 per cent anhydrous formic acid and 3.8 per cent water); a third suitable solvent is acetic acid containing no less than 5.7 vol. per cent water. By commingling the crude acids with a solvent of the type specified above, and employing suitable extraction conditions I can obtain naphthenic acids of any desired degree of purity. Preferably I employ countercurrent extraction with return of a portion of the extract to the extraction zone as reflux, and a preferred method of practicing my invention will now be described, reference being made to Fig. 1 of the accompanying drawings.

The crude naphthenic acids which it is desired to purify and which may comprise a mixture of naphthenic acids and neutral oil are withdrawn from tank 1 by pump 2 and pumped through line 3 to mixer 4 wherein they are mixed with the amount of solvent introduced through line 14 required to give a substantially saturated mixture which will not separate into two phases. The mixed crude naphthenic acids and solvent are then introduced into extraction column 5 at a point near the center and therein they are commingled with a relatively large amount of solvent. In the column 5 there flows downwardly an oil layer countercurrent to an upwardly flowing solvent layer that is in equilibrium therewith. At the top of the extraction column 5 a saturated solvent phase is removed through line 6 while from the bottom of the column 5 a saturated raffinate product is removed through line 7. The saturated solvent phase removed from the top of column 5 through line 6 is introduced into evaporator 1 wherein a sufficient quantity of solvent is distilled off, without changing the composition of the solvent, so as to yield a bottom product with a composition corresponding to a saturated extract phase.

This removal of solvent may be accomplished in any desired manner and is only diagrammatically illustrated in the drawings, the saturated solvent phase introduced into evaporator 1 is heated by steam coil 8 therein in order to vaporize the required proportion of the solvent and leave a saturated extract phase which is withdrawn from the bottom of evaporator 1 through line 9. A portion of the saturated extract phase flowing through line 9 is introduced through line 10 into still 11 wherein it is heated by steam coil 12, the solvent remaining therein being vaporized and removed overhead through line 13 to line 15, and flowing therethrough to condenser 16 wherein it is condensed and from which it flows through line 17 to solvent storage tank 18. From still 11 the refined naphthenic acids, free of solvent, are withdrawn through line 19 and flow to storage tank 20. A portion of the saturated extract phase withdrawn from evaporator 1 through line 9 is passed through line 21 to cooler 22 wherein it is cooled by indirect heat exchange to the temperature employed in extraction column 5 and after cooling is introduced through line 23 into the top of extraction column 5 to serve as reflux. The reflux ratio employed is that necessary to give a saturated solvent phase at the top of column 5 in which the naphthenic acids will be of the desired degree of purity.

The saturated raffinate product withdrawn from bottom of extraction column 5 through line 7 flows therethrough to heater 25 wherein it is heated to a sufficient temperature to vaporize the solvent on reduction of pressure and flows thence

through line 26 to flash tower 27 wherein the pressure is reduced and the solvent vapors formed are separated from the raffinate, the vapors being taken overhead through line 28, flowing therethrough to line 15 and thence to condenser 16 and solvent storage tank 18. The raffinate is removed from the bottom of flash tower 27 through line 29 and flows therethrough to raffinate storage tank 30. The remainder of the saturated raffinate product removed from the bottom of extraction column 5 through line 7 flows through line 31 to mixer 32 wherein it is mixed with solvent withdrawn from solvent storage tank 18 through line 33 and the mixture introduced as reflux through line 34 into the bottom of extraction column 5. A sufficient amount of saturated raffinate product is returned as reflux into the bottom of extraction column 5 in admixture with solvent from line 33 to give a saturated solvent phase which is substantially in equilibrium with the saturated raffinate product withdrawn from the bottom of the column. A sufficient quantity of solvent is introduced into the bottom of extraction column 5 through line 33 in order to effect the desired separation or degree of purity. The quantity of solvent is dependent on the reflux ratio that must be employed to make this separation. This reflux ratio will of course vary with the height of column, i. e. the number of theoretical plates or extraction stages, the composition of the feed, and the solubility relationships of the naphthenic acids, neutral hydrocarbon oil, and solvent.

For any given operation of the column there are actually two reflux ratios employed, one at the top of the column and the other at the bottom, and these are not necessarily the same. However, for any specified degree of separation of the feed components the two are related; thus for any given amount of reflux at one end of the column the reflux for the other end is fixed. Therefore, in specifying the column operation it is necessary to specify the reflux ratio at only one end of the column. Suitable mathematical and graphical methods of determining the necessary reflux are described by Varteressian and Fenske in Industrial and Engineering Chemistry, volume 29, Number 3, pages 270-277, March 1937, and need not be further described here.

However, in order to fully describe the present invention the following specific example is given. The crude naphthenic acids to be purified were obtained by the method disclosed in Terrell, Hughes and Carter Patent No. 2,056,913 and consisted of 75 per cent naphthenic acids and 25 per cent neutral oils by weight. It was desired to separate these acids into an extract comprising 98 per cent naphthenic acids and 2 per cent neutral oils. In order to effect the separation the crude acids were mixed with about 20 per cent by weight of a solvent comprising 73.5 per cent methanol and 26.5 per cent commercial formic acid by volume. The mixture which was obtained was substantially saturated and did not separate into two phases. This mixture was introduced into an extraction column at a point near the center thereof and was therein commingled with a large quantity of solvent. The saturated solvent phase was withdrawn from the top of column 5 through line 6 and this saturated solvent phase consisted of 80.6 per cent solvent, 19 per cent naphthenic acids and 0.4 per cent of neutral oil. The greater part of the solvent was removed from the saturated solvent phase by distillation in evaporator 1 so as to yield a saturated

extract product having a composition of 60.5 per cent naphthenic acids, 38.2 per cent solvent and 1.2 per cent oil. A reflux ratio of 1.3 to 1 was employed at the top of the columns and with this reflux ratio an extraction column having a height equivalent to six theoretical plates was required in order to effect the desired purification. Thus 1.3 parts of the saturated extract product withdrawn from evaporator 7 through line 9 were returned through lines 21 and 23 as reflux to column 5 to each part of saturated extract product withdrawn from the system through line 10. The saturated extract product withdrawn from the system through line 10, flowed to still 11, wherein in the remainder of the solvent was evaporated off to yield an extract consisting of 98 per cent naphthenic acids and 2 per cent neutral oil. From the bottom of extraction column 5 a saturated raffinate product comprising 73 per cent oil and 19 per cent naphthenic acids and 8 per cent solvent was withdrawn, and a sufficient amount of solvent to effect the desired separation was introduced at this point through line 34, such a portion of the saturated raffinate product flowing through line 7 being mixed therewith in mixer 32 as was required to give a solvent phase entering the extraction column which was in substantial equilibrium with the saturated raffinate product withdrawn therefrom.

In operating in the above manner, the exact amounts of the materials fed to the process and the products obtained for each hundred pounds of commercial naphthenic acids processed were as follows: One hundred pounds of commercial naphthenic acids which were composed of 74.1 pounds naphthenic acids and 25.9 pounds neutral oil were withdrawn from tank 1 and introduced through line 3 to mixer 4 wherein they were mixed with 23.2 pounds of the above identified solvent and the mixture then introduced into extraction column 5. At the bottom of column 5 586.1 pounds of solvent were introduced through line 34 from mixer 32 and line 33. At the top of column 5 through line 6 a saturated solvent phase composed of 662.5 pounds of solvent, 156.3 pounds of acids and 3.2 pounds of oil were withdrawn. In evaporator 7 563.5 pounds of solvent were evaporated to yield a saturated extract product which was withdrawn from evaporator 7 through line 9. A reflux ratio of 1.3:1 was employed at the top of extraction column 5 so the saturated extract product flowing through line 9 was split into two streams one of which amounting to 43 pounds of solvent, 68 pounds of acids and 1.39 pounds of oil was withdrawn from the process through line 18 while the other composed of 55.9 pounds of solvent, 88.4 pounds of acids and 1.81 pounds of oil was returned through line 21, cooler 22 and line 23 to the top of column 5 as reflux. From the bottom of column 5 there was withdrawn through line 26 a saturated raffinate product amounting to 2.78 pounds of solvent, 6.14 pounds of acids and 24.51 pounds of oil.

It should be understood that the foregoing is a detailed description of a preferred method of practicing the present invention and that various modifications and changes may be made therein without departing from the spirit of this invention or the scope of the appended claims. Thus, while it is preferred to add a sufficient

amount of solvent to the crude acids fed to the process to saturate the feed, it is of course possible to introduce the crude acids directly into the extraction column and by using a higher column saturate the feed in the column. It should also be understood that other extraction methods may be employed, although the method specifically described herein is preferred.

I claim:

10. 1. In the purification of naphthenic acids by solvent extraction, the method which comprises feeding crude naphthenic acids containing hydrocarbon oil to a countercurrent extraction zone between its ends, feeding into one end of said zone a solvent having preferential solvency for and incomplete miscibility with the naphthenic acids and comprising at least a major percentage of polar organic liquid, the solvent flowing through said zone countercurrently to the feed, withdrawing from the other end of the zone a saturated solvent phase and from the solvent-feed end of the zone a saturated raffinate phase, removing solvent from the saturated solvent phase to thereby separate a naphthenic acids-rich extract, returning as reflux to the solvent phase-withdrawal end of the extraction zone a part of said extract together with a minor proportion of solvent, and removing solvent from the raffinate phase to yield an oil-rich raffinate.
15. 2. The method defined in claim 1 wherein the solvent comprises a polar organic liquid containing a minor proportion of water.
20. 3. The method defined in claim 1 wherein the solvent comprises methanol containing not less than 12 volume per cent water.
25. 4. The method defined in claim 1 wherein the solvent comprises a major percentage of methanol and a minor percentage of formic acid and water.
30. 5. The method defined in claim 1 wherein the solvent comprises acetic acid containing not less than 5.7 volume per cent water.
35. 6. The method defined in claim 1 wherein the said feed is mixed, prior to its introduction into the extraction zone, with such minor proportion of said solvent that the mixture fed to said zone is substantially saturated with said solvent.
40. 7. In the purification of naphthenic acids by solvent extraction, the method which comprises feeding crude naphthenic acids containing hydrocarbon oil to a countercurrent extraction zone between its ends, feeding into one end of said zone a solvent having preferential solvency for and incomplete miscibility with the naphthenic acids and comprising at least a major percentage of polar organic liquid, the solvent flowing through said zone countercurrently to the feed, withdrawing from the other end of the zone a saturated solvent phase and from the solvent-feed end of the zone a saturated raffinate phase, removing solvent from the saturated solvent phase to thereby separate a naphthenic acids-rich extract, returning as reflux to the solvent phase-withdrawal end of the extraction zone a part of said extract together with a minor proportion of solvent, returning a portion of the raffinate phase to the extraction zone along with fresh solvent and removing solvent from the remainder of the raffinate phase to yield an oil-rich raffinate.
45. 8. The method defined in claim 7 wherein the solvent comprises methanol containing not less than 12 volume per cent water.
50. 9. The method defined in claim 7 wherein the solvent comprises acetic acid containing not less than 5.7 volume per cent water.
55. 10. The method defined in claim 7 wherein the solvent comprises a major percentage of methanol and a minor percentage of formic acid and water.
60. 11. The method defined in claim 7 wherein the solvent comprises a polar organic liquid containing a minor proportion of water.
65. 12. The method defined in claim 7 wherein the solvent comprises a polar organic liquid containing a minor proportion of water.
70. 13. The method defined in claim 7 wherein the solvent comprises a polar organic liquid containing a minor proportion of water.

WILMER E. MCCORQUODALE, JR.
